UNITED STATES PATENT OFFICE.

EDGAR L. DRINKWATER, OF CHICAGO, ILLINOIS.

PLINTH PLATE.

Application filed February 11, 1924. Serial No. 691,962.

To all whom it may concern:

Be it known that I, EDGAR L. DRINKWATER, a citizen of the United States, residing at Chicago, in the county of Cook and

5 State of Illinois, have invented certain new and useful Improvements in Plinth Plates, of which the following is a specification.

This invention pertains to plinth plates adapted for use in building constructions to 10 surround the horizontal branch pipes leading from the riser heating pipes to the radiators, the plates being employed for the purpose of covering the openings in the partitions from which the branch pipes emerge.

15 The openings through the partition walls must necessarily be large enough to afford considerable clearance around the pipes in order to permit the rise and fall of these pipes resulting from the longitudinal expansion and contraction of the riser pipes. In 20 order to produce a finished appearance the openings around the pipes must be covered, and one of the primary purposes of my present invention is to provide a plinth plate

25 which will cover these openings around the pipes and present a finished appearance where the pipes come through the baseboard or other portions of the wall and which will accommodate the movements of the pipes 30 caused by the expansion and contraction of the riser pipes. Another object is to provide a plinth plate which will permit the radiator branch pipes to be disposed in vertical alignment thereby eliminating the offsets and the expense of the elbows and labor 35 of installing such offsets heretofore considered necessary.

A further object is to provide a plinth plate of separable construction so that it 40 can be applied to the pipes after they have been installed. This feature is of material importance in building construction for the reason that it permits the radiator branches to be roughed in and the base trim to be installed and mitered at the corners whereupon 45 the plinth plate can be applied as the last operation. This feature enables the plinth plates to be plated or otherwise finished before installation. A separable plinth plate 50 of this character also permits of the installation and removal of the plinth plates to accommodate changes in partitions in ac-

cordance with the requirements of the building tenants both during and after construction and without disturbing the radiator 55 branch pipes.

The removal of the separable plinth plate further allows complete removal of the base wire slot cover and affords unrestricted access to the low tension wire slot, usually installed in the base in modern office building construction.

Other objects and advantages of this invention should be readily appreciated as the same becomes better understood by reference 65 to the following description when considered in connection with the accompanying drawings.

Referring to the drawings:

Fig. 1 is a fragmentary view of a building construction showing in elevation the installation of one of my improved plinth plates;

Fig. 2 is a vertical sectional view through a wall showing the installation of a pair of 75 plinth plates;

Fig. 3 is a face view of one of the duplicate sections of which my plate is composed.

Fig. 4 is an assembly view showing the two sections in assembled relation;

Fig. 5 is a sectional view on the line 5—5 of Fig. 4;

Fig. 6 is a sectional view on the line 6—6 of Fig. 1;

Fig. 7 is an end view of the plate section 85 illustrated in Fig. 3; and

Figs. 8 and 9 are fragmentary sectional views on the lines 8—8 and 9—9 of Fig. 4.

Referring now to the drawings more in detail, reference character 11 indicates generally a partition wall, formed customarily of tile or building blocks as illustrated, to which are attached the nailing strips or plaster grounds 12 to which the baseboard is secured. The baseboard may be of any preferred construction but in the present instance it is illustrated as being of the sectional type comprising a base member 13, a top member 14 and an intermediate removable member 15, the removal of which permits access to the space 17 behind the board in which the low tension electric wires for the building are disposed.

Reference characters 18 and 19 indicate

the branch pipes leading from riser heating pipes to a radiator, and while the riser pipes are customarily installed in a vertical partition wall or in a column, I have illustrated 5 in the present instance my invention as applied to a partition wall through which the branch pipes 18 and 19 extend. It should be manifest, however, that my invention is 10 equally applicable to the partitions or walls out of which the branch pipes emerge from the risers.

A plinth plate constructed in accordance with my invention comprises two duplicate preferably cast sections indicated generally 15 by reference characters 21 and 22, and since the sections are duplicates of each other, a detailed description of one of them should suffice for an understanding of the invention. Referring therefore more particularly 20 to the section 21, it will be observed that the section comprises a face plate 23 having a finished outer surface and provided on its rear face with a shallow rearwardly extending rib 24 disposed longitudinally of the 25 plate, the rib being terminated at its lower end as indicated at 25 and being provided near its upper end with a notch or recess 26 adapted to accommodate the lug 27 on the complementary section whereby the sections 30 are locked together against relative longitudinal displacement. As will be apparent from Fig. 3 each of the sections is substantially U-shaped, the leg 28 being shaped in cross section as illustrated in Fig. 6, and being 35 rearwardly offset from the face plate 23 to lie behind the rib 24 of the complementary section so as to leave a guideway between the ribs 24, and at the back of the face plates 23 between the rear surfaces of 40 these plates and the opposed edges of the legs 28, in which guideway the pipe embracing members, which will be later described, are disposed. This guideway is indicated in Figs. 5 and 8 by reference character 31. 45 A deep cross rib 32 extends from the upper end of the rib 24 transversely of the face plate 23 to the base of the leg 28 and this rib is equal in depth to the depth of the leg 28 plus the rib 24 so that when the parts are 50 assembled a rectangular frame is formed adapted to set into the opening in the baseboard as will be apparent from Fig. 2. The face plates present a finish over the frame and the shape of the plates is such that 55 when assembled they provide an elongated slot 33, Fig. 4, through which the pipes 18 and 19 extend as shown in Fig. 1.

The two complementary sections are held 60 against relative longitudinal displacement when in assembled position, by engagement of the lugs 27 in the notches 26, as previously described, and the sections are also held against relative lateral displacement or separation by the engagement of a lug 34 on 65 the back of each plate in a notch 35 formed

in the opposed forward edge of the cross rib 32. This construction is illustrated in detail in Fig. 9 and also in dotted lines in Fig. 4. The sections when in assembled relation form an escutcheon comprising a 70 slotted face plate the slot of which is surrounded by a rearwardly projecting flanged frame adapted to enter the opening in the baseboard or other portion of the wall from which the pipes project thereby permitting 75 the back of the face plate to lie snugly against the margins of the opening.

In the guideway previously described, which guideway is defined at its ends by the cross ribs 32 and at its sides by the ribs 24 80 and is produced by the spacing of the inwardly projecting portion 36 of the legs 28 away from the rear faces of the plates 23, as will be apparent from Fig. 6, are disposed filler plates one of which is indicated 85 by reference character 29 and the other by reference character 37. These filler plates are adapted to embrace the pipes 18 and 19 and while they may be of any preferred 90 construction such, for instance, as rectangular plates of relatively thin metal, each provided with a circular opening to receive a pipe and each being cut through from its margin to the opening at one side so that it can be twisted and slipped over the pipe, I prefer for convenience in manufacture and 95 assembly to employ filler plates formed of sheet metal and each slotted inwardly from one side to accommodate a pipe or pipes in the slot or slots with which each plate is provided. Each plate may be provided with one slot so that each pipe is embraced by two plates, in which entrance the plates 100 engaged with one pipe overlap the plates engaged with the other pipe, thus permitting relative vertical movement between the pipes, or only two plates, each having two slots, may be employed if preferred. When 105 these plates are slipped over the pipes from opposite sides and are disposed in the guideway of the escutcheon they embrace the pipes, overlap each other as indicated at 16, and close the slot 33 in the escutcheon thereby presenting a finished appearance to 110 the plinth plate. The filler plates, however, 115 are of such length and width that they are capable of vertical and horizontal sliding movements in the guideway to permit of the rise and fall and lateral movement of 120 the branch pipes due to expansion and contraction of the riser pipes without any movement of the escutcheon which is rigidly secured to the baseboard by a pair of wood screws 38 which in conjunction with the lugs and recesses previously described hold 125 the escutcheon sections against relative movement. The clearance between the edges of the plate and the guideways is indicated by reference characters 20 and 30.

In assembling the plinth plate around the 130

pipes already installed in the partition, the filler plates are first slipped onto the pipe from opposite sides, whereupon the escutcheon sections are positioned around the 5 pipes from the top and bottom respectively and brought together so as to dispose the filler plate in the guideway, whereupon the entire assembly is slid along the pipes to introduce the rearwardly projecting frame into 10 the opening in the baseboard and bring the face plates snugly against the margin of the opening, whereupon the assembled plate is secured to the baseboard by the screws 38. When thus assembled the clearance between 15 the pipes and the walls of the surrounding opening is entirely covered by the plinth plate so as to present a neat, attractive and finished appearance and the movability of the filler plates in the escutcheon guideway 20 permits of the requisite movements of the pipes without imposing any strain upon the plate or the wall and without leaving any opening into the space behind the baseboard. This construction furthermore permits the 25 pipes to be disposed in vertical alignment instead of being offset one relatively to the other as has heretofore been the practice, and this alignment eliminates the expense of the offsets, which because of the elbows 30 necessarily employed and the labor of threading and installing the offsets, has prior to my invention been an expensive feature of construction. The escutcheon sections being complementary and duplicates of each other 35 and being of cast construction can be very economically manufactured and the whole structure is capable of being easily and quickly assembled and installed after the branch pipes have been run and after the 40 baseboards have been mounted. Furthermore the ability to mount the baseboards and subsequently apply the plinth plates enables the baseboards to be extended through to the corners and mitered thus making a completely finished and desirable job. The application of the plinth plates at any time 45 and also the capability of removal when desired enables partitions to be built and removed as required without disturbing in any way the pipe connections. 50

I believe that the construction and many of the attendant advantages of my invention should be understood from the foregoing without further description and it should be 55 manifest that the structural details illustrated and described are capable of considerable modification without departing from the essence of the invention as defined in the following claims.

60 I claim:

1. A plinth plate comprising a slotted escutcheon composed of a pair of complementary U-shaped members, one leg of each member forming a section of a face plate 55 and the other leg being rearwardly offset

from said face plate, said members being provided with interengaging means whereby the members are held against relative longitudinal and lateral displacement.

2. A plinth plate comprising an escutcheon composed of a plurality of complementary sections, each of said sections being substantially U-shaped and having the legs thereof offset relatively to each other so that one leg of each member will be disposed rearwardly of the other leg of the other member when said members are assembled, said members being shaped to provide when assembled an elongated pipe receiving slot, and a guideway at the rear of said slot, and pipe engaging slot closing means slidably disposed in said guideway. 70 75 80

3. A plinth plate comprising an escutcheon composed of a pair of complementary interengaging sections, each section being of general U shape having one leg offset rearwardly relatively to the other, the forward leg being provided with a section of a face plate and the rear leg being laterally extended to form in conjunction with an opposed face plate a filler plate guideway, and a pipe embracing filler plate disposed in said guideway. 85 90 95

4. A plinth plate comprising an escutcheon composed of a pair of complementary sections, each section being formed to provide a portion of a face plate having a longitudinally extending rib on its rear face, a cross rib at one end thereof, and a leg projecting from one end of said cross rib in parallelism with said longitudinally extending rib, said leg being rearwardly offset relative to said rib and each of said sections being provided with interengaging elements whereby said sections are held against longitudinal and lateral displacement relative to each other. 100 105

5. A plinth plate as set forth in claim 8 in which the pair of complementary sections form when assembled an elongated slot 110 adapted to receive a plurality of pipes in vertical alignment.

6. A plinth plate as set forth in claim 8 in which the sectional escutcheon provides an elongated slot adapted to receive a plurality 115 of pipes in vertical alignment, and filler plates embracing said pipes and closing said slot, said filler plates being movable longitudinally of the slot with said pipes.

7. A plinth plate as set forth in claim 8 in which the sectional escutcheon form complementary sections providing a pipe receiving opening, and a pipe embracing filler plate slidably associated with said escutcheon and adapted to close said opening. 120 125

8. A plinth plate comprising an escutcheon composed of a plurality of interengaging sections adapted when assembled to provide a pipe receiving opening, each section being of general U shape with one leg offset 130

- relatively to the other so that said sections when assembled will present a flat front face.
9. A plinth plate comprising a plurality of U shaped sections, one leg of each section being provided with a section of a face plate, said sections when assembled providing an escutcheon having a center pipe receiving opening.
10. A plinth plate comprising a plurality of U-shaped sections, one leg of each section being provided with a section of a face plate, said sections when assembled providing an escutcheon having a center plate receiving opening, and filler plates adapted to embrace a pipe inclosed within said opening, said filler plates being movable relatively
- 15

to each other and relatively to said escutcheon in conformity with vertical or lateral movements of a pipe within said opening.

11. A plinth plate comprising a plurality of U-shaped sections, one leg of each section being provided with a section of a face plate, said sections when assembled providing an escutcheon having a center plate receiving opening, and a filler means adapted to embrace a pipe projecting through said opening and for closing the opening around said pipe, said means being movable relatively to the escutcheon in conformity with vertical or lateral movements of a pipe within said opening.

EDGAR L. DRINKWATER.
